United States Patent Office

Des. 191,357
Patented Sept. 19, 1961

191,357

RAZOR OR THE LIKE

Milton M. Sidney, White Plains, and David Woolley, Bronxville, N.Y., assignors to Mailman Bros., Mystic, Conn., doing business as Durham Enders Razor Company, a partnership

Filed Mar. 16, 1961, Ser. No. 64,346

Term of patent 14 years

(Cl. D22—3)

FIG. 1 is a front perspective view of a razor or the like, showing our new design;

FIG. 2 is a rear perspective view thereof;

FIG. 3 is a side elevational view thereof; and
FIG. 4 is a bottom elevational view thereof.

We claim:

The ornamental design for a razor or the like, substantially as shown.
